WIRE STRAIGHTENING DEVICE

William H. Buck, Buffalo, N. Y., assignor, by
mesne assignments, to Reconstruction Finance
Corporation, Boston, Mass., a corporation of
the United States

Application May 22, 1940, Serial No. 336,499

8 Claims. (Cl. 140—148)

The present invention relates to wire straightening or killing devices and embodies, more particularly, a straightening or killing device that permits the wire to be operated upon without subjecting the wire to a permanent set.

More particularly, the invention embodies a device of the above character that is particularly well adapted to be used with continuous wire drawing machines and operations and wherein a permanent set in the wire is avoided.

In continuous wire drawing operations, there is a tendency for internal strains to accumulate within the wire, resulting in the wire's becoming unmanageable by reason of its taking a permanent set around the wire drawing blocks. That is, wire with these internal strains, if coiled about the drawing blocks, assumes a permanent curvature less than the diameter of the block, or it may have what it called a "cast" or corkscrew condition from improper setting of the dies. When a coil of such wire is released and allowed to lie flat on the floor, the excess curvature or corkscrew condition present in the wire when first confined in a coil about the drawing block, causes the wire to become unruly, and when the wire is released from the confining bands, it tends to form corkscrews and become otherwise tangled.

A straightened or killed wire, on the other hand, has a curvature not much exceeding that of the wire when first confined in a coil, and if the wire is released on the floor it will remain in approximately one plane and will not tend to form corkscrews or become tangled. The "straightening" or "killing" of wire thus eliminates its otherwise normal tendency toward unruly behavior.

An object of the present invention is to provide a straightening or killing device by means of which wire may be straightened or killed effectively and without the difficulties attendant upon the presence of a permanent set formed in the wire.

A further object of the invention is to provide a wire straightening or killing device wherein the straightening or killing operation is performed without imparting a permanent set to the wire.

The foregoing objects are attained by providing a straightening or killing device wherein the elements over which the wire is passed are cooled in such fashion as to maintain the temperature of the wire below a value at which a permanent set in the wire would result.

Further objects of the invention will be ap-

parent as it is described in greater detail in connection with the accompanying drawing, wherein:

Fig. 1 is a plan view showing a wire straightening or killing device constructed in accordance with the present invention.

Fig. 2 is a view in front elevation of the device of Fig. 1.

Fig. 3 is a view in transverse section, taken on the line 3—3 of Fig. 2 and looking in the direction of the arrows.

Referring to the above drawing, the wire drawing device is shown as being formed with a base 10 having an elongated boss 11 which is provided with a plurality of threaded apertures 12. The base 10 is hollow and formed with a baffle wall 13 which divides the base into two compartments 14 and 15. The wall 13 terminates at 16 and thus provides communication between the chambers 14 and 15, as indicated at 17.

A flange 18 may be provided and formed with an aperture 19 by means of which the base may be securely mounted in position. At the other end of the base, threaded apertures 20 and 21 are provided by means of which a cooling fluid may be introduced into and withdrawn from the base. In order that the circulation of the fluid may be accomplished in a desired fashion, the aperture 21 communicates with the compartment 14, while the aperture 20 communicates with the compartment 15 and the cooling fluid must flow through the entire length of each compartment by reason of the baffle wall 13.

Within the threaded apertures 12, spindles 22 are inserted, the spindles being threaded to mate with the threads of the apertures 12, as shown at 23. Shoulders 24 may be formed on the spindles and suitable gasket or sealing material 25 provided to insure a fluid tight joint between the spindles and the base. Spindles are formed with axially hollow portions 26 and apertures 27 to facilitate movement of the cooling fluid into the spindles to effect the cooling thereof.

Rollers 28 are journaled on the spindles by means of roller bearings 29, the rollers being formed with grooves 30 over which the wire passes as indicated by the dot-and-dash line in Fig. 1. Counter pins 31 may be provided to secure the rollers in position on the spindles 22 and, in operation, the wire is drawn through the rollers to effect the straightening or killing thereof in accordance with well known practice. The circulation of a cooling fluid through the base maintains the spindles and rollers at such a temperature that undesirable heating of the

wire is avoided, thus preventing the formation of a permanent set therein with the resultant difficulty in handling the wire.

While the invention has been described with reference to the specific structure shown in the drawing, it is not to be limited save as defined in the appended claims.

I claim:

1. A wire straightening or killing device comprising a base, a plurality of spindles carried by the base, rollers on the spindles over which wire is passed to effect the straightening or killing thereof, said spindles and base being hollow, and means to introduce a cooling fluid into the base and spindles.

2. A wire straightening or killing device comprising a hollow base, a plurality of hollow spindles on the base and having the hollow portions thereof communicating with the hollow portion of the base, means on the spindles over which wire is passed to effect the straightening or killing thereof, and means to circulate a cooling fluid through the base.

3. A wire straightening or killing device comprising a hollow base, a plurality of hollow spindles on the base and having the hollow portions thereof communicating with the hollow portion of the base, rollers journaled on the spindles over which wire is passed to effect the straightening or killing thereof, and means to circulate a cooling fluid through the base.

4. A wire straightening or killing device comprising a hollow base, a plurality of hollow spindles on the base, and having the hollow portions thereof communicating with the hollow portion of the base, rollers journaled on the spindles over which wire is passed to effect the straightening or killing thereof, a baffle in the base, and means to circulate a cooling fluid through the base, said baffle directing the flow of the fluid along the spindles.

5. A wire straightening or killing device com-

prising a hollow base, a plurality of spindles on the base with a portion of each spindle extending into the hollow portion of the base, means on the spindles over which wire is passed to effect the straightening or killing thereof, and means to circulate a cooling fluid through the base and in contact with the spindles.

6. A wire straightening or killing device comprising a hollow base, a plurality of hollow spindles on the base with a portion of each extending into and having the hollow interiors thereof communicating with the hollow portion of the base, means on the spindles over which wire is passed to effect the straightening or killing thereof, and means to circulate a cooling fluid through the base and along the spindles.

7. A wire straightening or killing device comprising a hollow base, a plurality of spindles on the base with a portion of each spindle extending into the hollow portion of the base, means on the spindles over which wire is passed to effect the straightening or killing thereof, the extended portion of each spindle being provided with a passage therethrough, and means to introduce a cooling fluid into said base for circulation in contact with the extended portions of said spindles and through the passages contained therein.

8. A wire straightening or killing device comprising a hollow base, a plurality of hollow spindles on the base with a portion of each extending into and having the hollow interiors thereof communicating with the hollow portion of the base, means on the spindles over which wire is passed to effect the straightening or killing thereof, the hollow interiors of said spindles extending into the portion of the spindles adjacent which the wire is passed, and means to introduce a cooling fluid into said base for circulation about the extended portions of said spindles and into the hollow interiors thereof.

WILLIAM H. BUCK.
